UNITED STATES PATENT OFFICE.

EDWIN O. KLEMM, OF SAGINAW, MICHIGAN, AND EDWIN W. SCHREIBER, OF YUMA,
ARIZONA.

COMBINATION STUDY-CHAIR.

1,161,691.

Specification of Letters Patent. Patented Nov. 23, 1915.

Application filed December 2, 1913. Serial No. 804,299.

To all whom it may concern:

Be it known that we, EDWIN O. KLEMM and EDWIN W. SCHREIBER, citizens of the United States, residing at Saginaw, in the 5 county of Saginaw and State of Michigan, and Yuma, in the county of Yuma and State of Arizona, respectively, have invented certain new and useful Improvements in Combination Study-Chairs, of which the following is a specification.

The present invention relates broadly to improvements in furniture and particularly to combination study chairs of the adjustable reclining type.

15 The object in view is the provision of such a chair with a plurality of units, independent and adapted for different purposes and to this end we attach to the chair at various points about the same such elements as book shelves, an adjustable reading or book rest, a typewriter stand, magazine rack, and compartments, certain of said units being adapted to interlockingly coöperate with each other to enable compact arrangement and 20 incidentally afford additional functions for said units.

As this description proceeds it will be obvious that the aim of our invention is to provide an article of furniture particularly 30 useful to a student by means of which the occupant of the chair may so maintain within reach reference books, magazines and like necessary matter as to eliminate the necessity of moving therefrom and possibly interrupting the trend of thought by going to 35 a bookcase, desk, etc., for the information needed.

With the above and other objects in view, this invention consists in the construction, 40 combination and arrangement of parts all as hereinafter more fully described, claimed and illustrated in the accompanying drawings, wherein:

Figure 1 is a perspective view of a chair 45 constructed in accordance with our invention, the seat and back cushions therefor being omitted to show more clearly the details of construction. Fig. 2 is a front elevation. Fig. 3 is a top plan view. Fig. 4 is 50 a fragmentary sectional view taken about on the line 4—4 of Fig. 5. Fig. 5 is a view partly in section showing the interlocking coöperation of certain of the units provided on the chair. Fig. 6 is an enlarged detail

view showing more clearly the adjusting means for the chair back. Fig. 7 is a vertical sectional view through the book rest secured at one side of the chair. Fig. 8 is a vertical sectional view through the chair.

Throughout the following detail description and on the several figures of the drawings, similar parts are referred to by like reference characters.

The invention is shown in the drawings in its preferred embodiment and comprises a 65 chair of suitable material but preferably of sturdy construction so as to be capable of sustaining the various units connected therewith and to be more fully described hereinafter. The chair consists essentially of the 70 seat portion 1, an adjustable back 2, and wide arm rests 3 at each side of the chair connected to the top of the front legs 4 and rear legs 5.

Specifically describing the several features 75 of our invention it will be noted more clearly by reference to Fig. 6 that the back 2 of the chair is hingedly connected to the same so that said back may be adjusted at various 80 inclinations to enable the occupant of the chair to recline as desired. The adjusting mechanism comprises notched arcuate members 6 secured to the inner sides of the rear legs adjacent the back 2, through which passes transversely the rod 7. This rod has 85 formed thereon adjacent its extremities pawls 8 engaging in the notched members 6 to hold the back in adjusted position. At one side of the back and connected to the rod 7 is located a lever 9 by means of which the 90 rod 7 may be rotated in its bearings to disengage the pawls and vary the adjustment of the back 2, as desired. It is to be particularly noted that the handle 9 is so arranged that it will not require the occupant 95 of the chair to arise from the same in order to accomplish the adjustment of said back. At an intermediate point of the rod 7 extends rearwardly an arm 10 to the extremity of which is secured a spring 11 fastened at 100 its other end to the chair back, the function of said spring being to normally maintain the pawls 8 on the rod 7 in engagement with the arcuate members 6 and it will be obvious that to raise the back it is only necessary to 105 move the same forwardly, the pawls 8 sliding over the notches of the members 6 and rearward movement of said back is accom-

plished by manipulating the lever 9 as hereinbefore described. It will be noted by reference to Fig. 1 that the back 2 is formed with a plurality of open compartments 12 in 5 which may be placed magazines, papers and similar articles which are desired to be retained for reference purposes, and when the back cushion 13 is properly disposed in the chair, these compartments are effectively 10 covered in an advantageous manner. As before stated, the arm rests 3 are preferably wide, sufficiently so to be useful for writing or placing thereon articles for temporary use. Beneath the arm rests 3, at each side of 15 the chair and forming substantially lateral extensions for the chair seat are other shelves 14 also designed as a convenience for the reception of articles desired to be maintained near at hand.

20 Disposed at one side of the chair is a combination book shelf and magazine rack 15 which is suitably fastened removably to the chair by means of bolts 16 and adjusting nuts 17 thereon. As shown in Figs. 1 and 8 this unit has adjacent its upper portion a shelf 18 on which books may be placed while beneath said shelf unit is preferably provided a plurality of slats 19 forming the magazine rack. The base portion of the rack is divided from the shelf 14 adjacent thereto by the partition 20 most plainly seen in Fig. 8 of the drawings and this partition is designed to prevent magazines placed in the rack from sliding out onto the shelf 35 aforesaid.

One of the important features of the chair construction, referring particularly to its legs, is that they are of a sufficient size to permit of installation of sliding compartments or drawers 21, one of said drawers being disposed in each of the front legs 4 so as to slide inwardly toward each other. These are disposed in the legs a sufficient distance above the seat so as to permit their movement without contact with the legs of the occupant of the chair and are designed particularly to accommodate card indexes or to be used for other desired purposes. The legs 4 of the chair being hollow, the space 45 beneath the drawers may be utilized if desired.

50 Secured to the front leg 4 at one side of the chair is provided an adjustable book rest 22 while at a corresponding point of the front leg at the opposite side is a swinging stand 23. These units are designed to cooperate in an advantageous manner more clearly to be set forth hereinafter. The adjustable book rest 22, specifically, is swivelly 55 mounted upon the outer extremity of an arm 24 which at its inner extremity is pivotally mounted in a bracket 25 secured beneath the arm rest 3, at the right side of the chair. The board of the rest 22 is provided at a 60 point adjacent its top portion with a book

ledge 22' to be used mainly for a large book such as a dictionary and at its lower portion with a second ledge 22'' for a reference or reading book. The rest 22 is held at suitable inclinations by means of the adjusting bar 26 which is hingedly connected in rear of the rest as shown most clearly in Fig. 7 of the drawing. The member 26 is formed with a plurality of notches 27 and said bar is movable through an opening 28 in the base 29, on which the rest 22 is hinged at 30. As will be obvious the inclination may be adjusted by this bar 26, the edge of the opening 28 with which the notches 27 co-operate being suitably recessed so as to insure positive engagement of the bar in adjusted position. The stand 23 on the opposite front leg 4 is movable in a manner similar to the rest 22 to a point in front of the occupant of the chair and is designed to accommodate various articles particularly a typewriter. As shown in Fig. 3, the stand 23 is formed with an opening 23' therethrough and when the stand is swung into a position in front of the chair shown most clearly in Fig. 5, and the adjustable book rest 22 is swung likewise, the bar 26 is disengaged from the edge of the opening and passed through the opening 23' of the stand 23. In the horizontal position of the book rest shown in the Fig. just mentioned, the rest is adapted for use as a table for writing purposes, or otherwise, and it is particularly desired that such unit may be rendered substantially rigid and to this end the bar 26 is engaged with the edge of the opening 23' of the stand 23 so as to sustain the rest when in horizontal position in co-operation with the pivot of the arm 24. It will thus be obvious that the member 22 performs a dual function acting in one instance as an adjustable book rest and in a second instance as a table. In a similar manner the stand 23 serves a dual function in that it may support an article disposed thereupon under ordinary use of the chair and forms an interlocking member for holding the rest in its inwardly swung position, supporting such rest advantageously. This interlocked position of the two units described enables 100 these parts to be assembled in compact form for moving the chair from one place to another and eliminates the necessity of removal of the parts therefrom. Beneath the book rest 22 is slidably mounted a drawer or 105 compartment 22^a in which a supply of stationery may be placed. As most clearly shown in Fig. 4 of the drawings the typewriter stand 23 is mounted at the outer end of the arm 31 which is pivotally supported at its inner end by the bracket 32 and both the arms 24 and 31 may be removed from their brackets by loosening the pivot pins 24' and 31' respectively on which they are 110 mounted.

Having thus described the invention, what we claim as new and desire to secure by Letters Patent is:

1. In a chair of the class described, the combination of an adjustable book rest connected thereto at one side of the same, a horizontally swinging arm carrying the rest, a typewriter stand disposed at the opposite side of said chair, an arm for said stand 10 pivotally secured to the chair for swinging in a different horizontal plane than the book rest arm, and means on the book rest adapted to engage the typewriter stand to support said rest and lock said stand and 15 rest against rotation when the rest and stand are swung into a position in front of the chair, said means constituting the adjusting means for the book rest.
2. In a chair of the class described, the combination of an adjustable rest, a support 20 for said rest, swingingly connected to the chair at one side of the same for movement of the rest into position in front of said chair, a movable stand disposed at the opposite side of said chair and adapted to swing 25 in front thereof, and means for adjusting the rest at different inclinations, the stand having an opening therethrough to receive

said adjusting means when moved into the position aforesaid and thereby interlock the 30 rest and stand in coöperative relation.

3. In a chair of the class described, the combination of an adjustable book rest, an arm pivotally connected to the chair at one side thereof upon which said rest is pivotally connected, a typewriter stand disposed at the opposite side of said chair, an arm swingingly connected to the chair upon which the stand is mounted, a member for adjusting the rest at different inclinations 35 to form an adjustable book rest, said member being adapted to interlock with the typewriter stand to support the book rest in a horizontal position when the stand is swung in front of the chair. 40

In testimony whereof we affix our signatures in the presence of two witnesses.
